UNITED STATES PATENT OFFICE.

GEORGE LAWSON McCALLUM, OF CROSBY, PENNSYLVANIA.

DOOR FOR BOX-CARS.

1,373,516.

Specification of Letters Patent.

Patented Apr. 5, 1921.

Application filed February 24, 1919. Serial No. 278,862.

To all whom it may concern:

Be it known that I, GEORGE LAWSON McCALLUM, a citizen of the United States, residing at Crosby, in the county of McKean 5 and State of Pennsylvania, have invented a new and useful Door for Box-Cars, of which the following is a specification.

This invention relates to improvements in doors for box cars, the object of the invention being to provide a door which is specially adapted for cars carrying grain, by means of which the door-opening may be partly closed at the bottom, leaving the upper part open for permitting access to the 15 grain, and in which the door is securely locked both in open and closed positions.

A further object of the invention is to provide a door of this character formed of a plurality of independently slidable sections, whereby some or all of such sections 20 may be slid into position to close the door-opening and each section provided with means for locking it in open or closed position independently of all the other sections.

25 A further object of the invention is to provide a shield in which each of the sections of the door is adapted to slide and which not only acts as a guide for said section, but also sustains the pressure of the 30 grain within the car so that the sections of the door may be as easily operated when the car is loaded as when empty.

With these and other objects in view, which will appear as the description 35 proceeds, my invention resides in the novel features of construction and combination of parts, as will be clearly understood from the following description.

In the drawings accompanying and forming 40 part of this specification,

Figure 1 is an elevation showing so much of the inner side of a box car as is necessary to illustrate my improved door in position for closing the door-opening of the 45 car, the two uppermost slides of the door being shown in dotted lines within their shields or casings;

Fig. 2 is a perspective view showing two of the slides partly withdrawn from the 50 shields;

Fig. 3 is a side elevation showing the rib formation on the side of the slides which lies next to the side of the car;

Fig. 4 is a longitudinal section of the 55 slide shown in Fig. 3; and

Fig. 5 is a sectional detail view showing

the formation of the lowermost shield and its slide.

The same characters of reference designate the same parts in all the figures of the 60 drawings.

In the embodiment herein shown, my improved door is constructed of a plurality of sliding members which are adapted to close the opening of the door, and a plurality of shields within which said members are adapted to slide for opening and closing the door, and as all of the slides and shields respectively, with exception of the lowermost one, are of similar construction, 70 a description of one will suffice for all of the shields and slides above said lowermost one.

In the form shown in the drawings, 2 designates the shields, which are adapted to be secured to the opposite sides of the door-opening 3 of the car, those at one side of said opening being located in staggered position relatively to those on the other side of such opening. The shields 2, the construction of which is best shown in Fig. 2, 80 are provided with flanges 4 along the sides and inner ends thereof and extending at the outer end of the shield into a pair of laterally projecting ears 7, the ears of adjacent shields being adapted to abut against each 85 other and form spacing members therebetween. Through the flanges 4 and the ears 7 are bored holes 5 for the passage of the screws by which the shields are secured to the side wall of the car. The shields and 90 flanges may be made separately and secured together in any suitable manner, or they may be made from one piece of metal stamped or pressed up into the desired form.

The shield is formed at its inner end with a 95 depending portion 6 forming a channel communicating with the interior of the shield, whereby any grain that may have been carried into the shield will be discharged, as will any dust or dirt that may have accumulated within the shield. At the opposite or outer end, the shield 2 is provided with angular portions 8 extending laterally of said shield, but shorter than the ears 7, thereby forming a space between the portions 8 of 100 adjacent shields, as shown at 9, Fig. 2, for a purpose to be hereinafter described. The outer end of the shield is also provided with a recess 10 and an eye member 11 back of said recess, this eye member being either 105 formed integral with the shield or secured thereto in any suitable manner. A similar

eye-member 12 is mounted on the framework of the door-opening immediately back of the abutting ears 7 of each pair of shields, a convenient form of such eye member being 5 shown in Fig. 2.

The slides 15 adapted for coöperation with the shields above described are shown herein as of groove and tongue formation on their opposite edges, the groove 13, (see 10 Fig. 2), in the edge of one slide engaging the tongue 14 formed on the adjacent edge of the next slide. This groove and tongue connection, while permitting the slides to move relatively to each other, forms a tight 15 joint and affords added strength and rigidity to the door when closed, and, in addition, assists in guiding the slides when being opened or closed. The slides are formed smooth on one side, as shown in Fig. 2, and on the opposite side with longitudinally and transversely extending ribs 16, as shown in Fig. 20 3, which ribs materially stiffen the slides and consequently the door when closed. Each of the slides is provided at its inner 25 end with a projecting lug 17, which serves to prevent complete withdrawal of the slide from the shield, a groove being formed in the side wall of the car for permitting this lug to slide back and forth, as shown in Fig. 30 5. At the outer end thereof the slide is provided with a hook 18 secured thereto by means of an eye member 19, which may be either formed on the slide or secured thereto in any suitable manner. The hooks herein 35 shown are of a form similar to those used on harness hames and having a spring-pressed locking plunger which prevents the hook from becoming accidentally disengaged from the eye member to which it is adapted 40 to be hooked.

It is believed that the operation of the slides and shields so far described will be clear from the foregoing. When the slides are slid back within the shields or casings 2, 45 the members 19 carrying the hooks are located within the recesses 10 in the shields and the hooks 18 are turned backward and hooked into the eye members 11 on the shields. When the slides are withdrawn 50 from the shields for closing the door-opening, the forward end of each slide projects beneath the forwardly projecting part of the angular portions 8 of two adjacent shields on the opposite side of the door-opening, while the eye member 19 carrying the hook 18 is located within the recess 9 formed between such angular portions, the side walls of such recess coacting with the rear portion of the hook to prevent the end 55 of the slide from moving up or down. The hook is then hooked into the eye member 12 in the rear of such recess, whereby the slide is positively locked against accidental displacement.

60 65 The formation of the lowermost shield,

as hereinbefore stated, is somewhat different from that of the others, said lowermost shield being shown in side elevation at the left of Fig. 1 and in section in Fig. 5. This shield, designated 20, is provided at its 70 rear end and upper side with a flange similar to the flanges of the upper shields. The upper portion of the front end of this shield is also similar in form to the corresponding portions of the other shields, and it is provided with an eye member 11 in the same manner as are all the other shields. The lower portion of the shield 20, however, is cut away, as shown at 21, so as to afford access to the interior of the shield when the 80 slide is withdrawn therefrom, for the purpose of clearing away any grain or dirt that may have accumulated therein. The shield 20 is provided at several points along its lower edge with L-shaped projections 22 85 adapted to rest on the floor and each provided with a hole for the passage of a screw for securing said projections to the floor of the car. For the purpose of strengthening the shield, it is formed with a lengthwise 90 extending rib 23 formed on its outer side, as clearly shown in Fig. 5. The slide co-operating with this shield is identical with those already described, and when within the shield its hook may be engaged with the 95 eye member formed at the outer side of said shield, while, when it is withdrawn from the shield the forward end thereof engages beneath the lower forwardly projecting part of the angular member 8 of the shield next 100 above and its hook is engaged with the eye member 12 carried on the door frame in the rear of said angular member. In the manufacture of the door described it is contemplated making three or more of the lower 105 shields somewhat heavier than the upper ones so as to be capable of sustaining the greater weight of grain that necessarily bears against the lower shields.

It will thus be seen that I have provided 110 a door which is well adapted for the purpose set forth, which is comparatively simple in construction, economical to manufacture and very practical in use, and while I have described in detail the features of construction 115 herein illustrated I do not desire to limit my invention to the precise structure shown, as I am aware that many mechanical changes may be made without departing from the spirit and scope of the invention 120 as set forth in the appended claims.

Having thus described my invention, what I claim is:

1. A door of the class described, comprising a plurality of slidable members, shields or casings mounted at opposite sides of a door opening, those at one side being located in staggered relation to those at the opposite side, said shields being adapted to receive said slidable members, and coöperating 125 130

means carried by said slidable members and shields for locking said members in door-opening position, the adjacent shields having flanges at their inner ends spaced apart 5 to provide slots for receiving said coöperating means carried by the slidable members.

2. A door of the class described, comprising a plurality of slidable members adapted to close a door opening, shields or casings 10 mounted at opposite sides of said door opening and adapted to receive said slidable members, coöperating means carried by said slidable members and shields for locking said members in door-opening position, and 15 coöperating means carried by said slidable members and shields for preventing upward or downward shifting of the slidable members when in door-closing position, the inner ends of the shields being flanged to receive 20 the ends of opposed slidable members when in closed positions.

3. A door for box cars or the like comprising a plurality of slidable members, shields mounted at each side of the door 25 opening in horizontal parallel relation and in staggered relation to the shields on the opposite side of the door opening, said shields being elongated horizontally, said slidable members having coacting edge portions 30 interrupting the direct line of continuity therebetween, said shields being provided with openings in their bottom portions adjacent their outer ends, and fastening mem-

bers upon and between the shields and close to the sides of the door opening, and means 35 upon the free end portions of the slidable members for engaging the fastening members on the shields of said slidable members to hold the slidable members in open position and for engaging the fastening members between the shields at the opposite side of the door for holding the slidable members in closed position across the door opening.

4. A door of the class described comprising guide casings secured in staggered relation at opposite sides of a doorway, said casings having means for attaching the same and provided with recessed flanges at their inner ends, door sections slidably received in said casings and provided with 50 co-acting tongue and grooved upper and lower edges, said sections having longitudinal reinforcing ribs, means carried by the sections and support for the casings to limit the movements of the sections in the casings, 55 and coöperating means carried by said casings, sections and support for securely holding said sections in position to open or close said doorway.

In testimony that I claim the foregoing 60 as my own, I have hereto affixed my signature in the presence of two witnesses.

GEORGE LAWSON McCALLUM.

Witnesses:

GEORGE A. DENNING,

THOMAS J. McDERMOTT.
